UNITED STATES PATENT OFFICE.

MORITZ L. MUELLER, OF SEATTLE, WASHINGTON, ASSIGNOR OF ONE-HALF TO HENRY BERT FRYER, OF SEATTLE, WASHINGTON, AND ONE-HALF TO NORTHWEST BLOWER KILN CO., OF SEATTLE, WASHINGTON, A CORPORATION OF WASHINGTON.

BARREL-DRYING KILN.

Application filed May 1, 1922. Serial No. 557,636.

To all whom it may concern:

Be it known that I, MORITZ L. MUELLER, a citizen of the United States of America, and resident of the city of Seattle, in the county of King and State of Washington, have invented certain new and useful Improvements in Barrel-Drying Kilns, of which the following is a specification.

My invention relates to dry kilns and particularly to kilns designed for drying barrels or analogous material. While the kiln has been especially designed for drying barrels, it is of course, applicable to drying other material and is not limited to use with barrels.

The object of my invention is to provide a kiln in which such articles as barrel bodies, or staves in the form of a barrel without heads thereon, may be dried so as to properly set the barrel staves in the shape of the completed barrel.

My invention consists of certain novel features of construction which are illustrated in the accompanying drawings and which will be hereinafter described. The parts thereof which are deemed to be novel and patentable will be defined in the claims terminating this specification.

The accompanying drawings show my invention embodied in the type of construction which I now prefer.

Figure 1 is a transverse sectional elevation of a kiln embodying my invention.

Figure 2 is a horizontal longitudinal section of the receiving end of the kiln, and Figure 3 a like view of the discharge end of the kiln, the same being broken away at different levels in order to show various features of construction.

Figure 4 is a longitudinal vertical section showing the discharge end of the kiln.

In the manufacture of barrels which are given a taper or bulge, it is the common practice to give the staves otherwise finished, a steaming process until they are in condition for proper setting, then to assemble these in the shape of the completed barrel, securing them by hoops and then drying the barrels in this shape until the staves have been set. The usual manner of heating and drying these staves has been to place them over a pot which contains burning fuel such as charcoal or coke, the heat from this acting solely upon the interior surfaces of the

staves and giving them their final set. It has been found that this method of procedure injures a considerable percentage of the barrels by overheating or burning the inner surface of the staves, thus making these barrels culls, unfitted for high class use and relegating them to a low class of use for which the value is less than were the case had they not been injured during the drying process.

It is the object of my invention to secure uniformity in drying the staves, and to dry the staves both from the outside and the inside, thus avoiding the injury so commonly caused by the old process of drying over a fire. My present invention consists of a kiln having means for passing the assembled barrel bodies, minus their heads, slowly and regularly through the drying chamber, subjecting them during this process to heat applied both externally and internally, as by the use of radiating pipes located at the side of the barrel and above the barrels, while at the same time causing circulation of the drying air through the barrel lengthwise thereof.

In the type of kiln herein illustrated, I employ a central drying chamber 1 which has therein endless conveyors, 2, extending throughout the length of this drying chamber and also into the receiving and discharge chambers 10 and 11 which are located at the respective ends of the kiln. The receiving chamber 10 is of sufficient length to receive a number of the barrels and is connected with the drying chamber by means of hinged doors, as 12, which are adapted to swing inward and may be operated either by hand or by a barrel carried by the conveyor 2. This chamber is also provided with hinged doors, as 13, at its outer end so that the chamber may be entirely closed against the outside air when desired. The outer doors 13 would ordinarily be closed most of the time.

The drying chamber has, extending along the sides thereof, heat radiating pipes as 3. It also has beneath the ceiling, other heat radiating pipes as 30. The ceiling 14 is located just above the pipes 30 and these pipes 30 are supported upon beams 31 which extend transversely of the drying chamber and at such a height as to provide free space for the passage of the largest barrels which

- are to be dried. Above the ceiling 14 is a chamber 4 and beneath the floor 15 is a chamber 40. These serve, respectively, as supply and return flues for the hot air. 5 These are connected at one end of the kiln with positive circulating means, indicated in Figure 3 as a fan located at the point 41. This is connected with the respective flues by pipes or flues 42 and 43.
- 10 The supply flue 4 is connected with the drying chamber by a series of openings and with deflecting plates as 44. These are distributed throughout the length of the drying chamber and are located directly above the endless conveyors 2. Two sets of such conveyors are employed, located symmetrically at opposite sides of the central line and each consisting of two chains or belts. These conveyors are provided with lugs or any other means which will enable them to positively engage and carry along the barrel bodies after they have been placed thereon. In using the kiln for drying barrels or kegs of moderate size, two rows would be passed through the kiln at the same time. If, however, it be desired to dry hogsheads or casks too large to permit passage of two rows, a single row would be employed, as is indicated by the barrel 5 shown in Figure 2.
- 25 30 The relative position of the smaller sizes is indicated by the barrel bodies 50.

The floor of the drying chamber is provided with discharge slots 6 located one under each row of the smaller sized barrels, that is, between the companion belts or chains 2 which form one of the conveyors. These discharge slots are preferably made of somewhat greater width than the end of the kiln which is distant from the fan than they are at the end which is next to the fan. The object of this is to insure drawing air from the far end of the kiln, at approximately the same rate as it is withdrawn from the near end. The floor of the kiln is also provided with holes as 60, in which is located one of the wheels over which the conveyor passes. The conveyor may be actuated by any suitable means. Actuating means, therefore, has not been illustrated.

50 It is designed, for the particular work mentioned, namely, the drying of barrels which have just been set up, that superheated steam be employed. By this expedient a sufficiently high temperature may be given the air so that the barrels may be quickly dried. If sufficiently high temperature be employed, the barrels will be properly dried so as to give the staves a satisfactory permanent set during their passage through the drying chamber. They may then, if this be desired, be knocked down, bundled and shipped, it being certain that they will retain their proper bent shape.

55 60 65 What I claim as my invention is:

65 70 75 1. A dry kiln for barrels comprising a

drying chamber, means for conveying barrels lengthwise of and through said chamber, the floor and ceiling of said drying chamber having, one air inlet openings and the other air discharge openings distributed along the 70 length of the chamber whereby air may be passed both through and around the barrel as it passes through the drying chamber.

2. A dry kiln for barrels comprising a drying chamber, an endless conveyor extending lengthwise therethrough, air flues extending lengthwise both above and below said chamber, the floor of said chamber having a slot extending lengthwise beneath the barrels as they pass through the chamber, 80 and the ceiling having air passages extending lengthwise thereof and connecting it with the upper flue.

3. A dry kiln for barrels comprising a drying chamber, means for conveying barrels lengthwise of and through said chamber, the floor and ceiling of said drying chamber having, one air inlet openings and the other air discharge openings distributed along the length of the chamber whereby air may be passed both through and around the barrel as it passes through the drying chamber, 90 and steam pipes located beneath the ceiling through which pipes the air passes before engaging the barrels. 95

4. A dry kiln for barrels comprising a drying chamber, means for conveying barrels lengthwise of and through said chamber, the floor and ceiling of said drying chamber having, one air inlet openings and the other air discharge openings distributed along the length of the chamber whereby air may be passed both through and around the barrel as it passes through the drying chamber, and heat radiating pipes placed beneath the ceiling and at each side of the drying chamber. 100

5. A dry kiln for barrels comprising a drying chamber, means for conveying barrels lengthwise of and through said chamber, the floor and ceiling of said drying chamber having, one air inlet openings and the other air discharge openings distributed along the length of the chamber, said openings in the floor consisting of a slot located under the path of travel of the barrels through the kiln. 110

6. A dry kiln for barrels comprising a drying chamber, means for conveying barrels lengthwise of and through said chamber, the floor and ceiling of said drying chamber having, one air inlet openings and the other air discharge openings distributed along the length of the chamber, said openings in the floor consisting of a slot located under the path of travel of the barrels through the kiln, said slot being wider at one end of the kiln than at the other end. 120

7. A dry kiln for barrels comprising a 125

drying chamber, air conveying flues located above the ceiling and below the floor of said drying chamber, an air circulating means connecting said flues at one point, said flues being connected with the drying chamber throughout its length to thereby produce a vertical movement of air across the drying chamber throughout its length, and means for conveying the open ended barrels slowly 10 through the drying chamber while in a vertical position.

8. A dry kiln for barrel bodies comprising a drying chamber, a receiving and discharging chamber at opposite ends of the 15 drying chamber, swinging doors connecting said receiving and discharging chambers with the drying chamber, barrel conveyors extending through the drying chamber and into each of the receiving and discharging 20 chambers, doors closing the outer ends of said receiving and discharging chambers and means for producing circulation of air

across the drying chamber in the direction of the axes of the barrels being passed therethrough.

9. A dry kiln for barrel bodies comprising a drying chamber, a receiving and discharging chamber at opposite ends of the drying chamber, swinging doors connecting said receiving and discharging chambers 30 with the drying chamber, barrel conveyors extending through the drying chamber and into each of the receiving and discharging chambers, doors closing the outer ends of said receiving and discharging chambers, 35 supply and return flues located respectively above and below the drying chamber, the ceiling and floor of the drying chamber having openings communicating with said flues, and means for inducing circulation through 40 said flues and openings.

Signed at Seattle, King County, Washington, this 21st day of April, 1922.

MORITZ L. MUELLER.
